GOVERNOR FOR REGULATING SPEED OF
WATER WHEELS

Nelson J. Pepin, Lowell, Mass.

Application January 15, 1941, Serial No. 374,595

3 Claims. (Cl. 137—158)

This invention relates to water wheels and more particularly to an automatically operable means for regulating the speed of the water wheel.

An object of this invention is to provide a regulating means for use with a water wheel, such as a turbine or other conventional water operated power member wherein the flow of the water to the wheel or power member is automatically regulated in accordance with the speed of the power member.

Another object of this invention is to provide a regulating means or governor for a water wheel or power member, which is operated by vacuum or suction developed from the flow of the water after it has passed the power member, the suction being communicated to a suction operated power device, which is connected to a valve or other water regulating means for regulating the volume of water passing through or engaging the wheel.

A further object of this invention is to provide a speed regulating means of this kind which may be connected to any suitable water driven power wheel or turbine which is simple in construction so that it may be operatively connected with the water wheel or power member without affecting the present parts of the power member.

A further object of this invention is to provide a governor for regulating the speed of water wheels in which governor will be actuated by vacuum or suction created in the water wheel draft tube or by vacuum or suction created by a pump or by any other means.

To the foregoing objects and to others which may hereinafter appear, the invention consists of the novel construction, combination and arrangement of parts as will be more specifically referred to and illustrated in the accompanying drawings wherein are shown embodiments of the invention, but it is to be understood that changes, variations and modifications may be resorted to which fall within the scope of the invention as claimed.

In the drawings:

Figure 1 is a detail side elevation partly in vertical section of a regulating means constructed according to an embodiment of this invention connected with a conventional power wheel.

Figure 2 is a detail front elevation partly broken away and in section of the device.

Figure 3 is a sectional view taken on the line 3—3 of Figure 1.

Referring to the drawings, the numeral 10 designates generally a flue or duct through which water is adapted to pass, the flue 10 being provided with an elbow 11 and a discharge duct 12

connected to the elbow 11 and disposed in a vertical position. The discharge member 12 is of flared construction and is provided at its upper end with a flange 13 which engages a flange 14 carried by the elbow 11. The two flanges 13 and 14 are connected together by fastening devices 15. A power member generally designated as 16 is disposed within the flue 10 and this power member 16 may be either a water turbine or other suitable water driven power member. A drive shaft 17 is rotated by operation of the power member 16 and in the present instance extends axially of the flue 10 and projects outwardly through the elbow 11, being journaled in a bearing 18 which is formed with the elbow 11.

The shaft 17 may be extended to the desired point and connected with power driven devices.

In order to provide a means whereby the power member 16 may be automatically regulated as to speed, I have provided a governor generally designated as 19. The governor 19 includes a shaft 20 which is journaled in a bearing 21, which may be fixed to the elbow 11 in any suitable manner. The shaft 20 has mounted thereon a driven pulley 22 and the drive shaft 17 has mounted thereon a driving pulley 23. An endless belt 24 is trained about the two pulleys 22 and 23 so that the driven shaft 20 will be rotated from the drive shaft 17. A valve housing 25 is mounted on a bracket or supporting arm 26, which is secured to the elbow 11, the arm 26 being provided with a substantially right angular base plate 27, which is secured by fastening devices 28 to the elbow 11 below the drive shaft.

The valve member 25 comprises a cylindrical valve housing 29, a bottom wall or plate 30, which is fixed to the cylindrical housing 29 by any suitable fastening means and the bottom wall 30 is secured as by a fastening device 31 to the upper side of the supporting arm 26. A top wall 32 is secured to the cylindrical housing 29 by fastening devices 33 and a valve operating shaft 34 is slidable and rotatable through the top wall or head 32. The shaft 34 has secured thereto a spool-like valve plug generally designated as 35, which is slidable and rotatable in the valve housing member 29. The valve plug 35 comprises a pair of cylindrical upper and lower port closing members 36 and 37, respectively, and an intermediate cylindrical member 38, which is of a reduced diameter from the upper and lower valve port closing members 36 and 37 thereby providing a chamber 39 between the inner ends of the port closing members 36 and 37.

A bevel gear 40 is fixed to the horizontal shaft

20 adjacent the pulley 22 and a second bevel gear 41 is mounted on the shaft 34, the shaft 34 being keyed as by a key 42 to the gear 41 so that the shaft 34 may have a vertical sliding movement relative to the bevel gear 41 but is held against rotation relative thereto. A boss or hub 43 is carried by the gear 41 on the upper side thereof and is provided with a pair of diametrically opposed slots 44 in which a pair of link members 45 are pivotally mounted.

A second pair of link members 46 are pivotally connected as at 47 to the upper ends of the links 45 and a weight 48 is also carried by each pivot 47. An annulus or sleeve 49 is fixed as by a pin 50 on the upper portion of the shaft 34 and the sleeve or bushing 49 is provided with pairs of diametrically opposed ears 51 between which the upper ends of the links 46 are pivotally mounted as at 52. A collar 53 may also be secured as by a pin or fastening member 54 to the upper end of the shaft 34. A spring 55 is mounted about the shaft 34, the lower end of the spring 55 bearing against the boss or hub 44 and the upper end of the spring 55 bearing against the sleeve or bushing 49. In this manner, the links 45 and 46 will be constantly urged to a substantially aligning position for holding the valve plug or member 35 in its uppermost port opening position. The gear 41 is held against upward movement on the shaft 34 by means of a collar or ring 56 which engages about the hub 43, the hub 43 being substantially smaller in diameter than the largest diameter of the gear 41. The annulus or ring 56 is held in a fixed position by means of a substantially U-shaped supporting member 57 which has an upper leg thereof integral with the ring 56 and which has the lower leg 58 thereof mounted on the head 53 and secured by a fastening device 59.

The valve housing member 29 is provided with a suction port 60 in which a suction pipe 61 is mounted. The suction port 60 is substantially midway between the head 32 and the base 30 and the pipe 61 extends horizontally from the valve housing member 29 and is provided with an extension 62 which extends through a boss 63 provided in the elbow 11. The extension 62 terminates in a downwardly extending suction nozzle 64 positioned within the elbow 11 so that the downwardly moving water passing the suction nozzle 64 will generate a partial vacuum in the extension 62 and in the suction pipe 61. The valve housing member 29 is also provided with an upper suction port 65 and a lower suction port 66. A pipe 67 is connected to the upper suction port 65 and a lower pipe 68 is connected to the lower suction port 66.

A suction motor generally designated as 69 is supported from the power member 16 by means of a supporting member 70 and the suction motor 69 comprises an elongated cylinder 71 having heads 72 and 73 at each end thereof. The suction pipe 67 is connected to the head 72 and the suction pipe 68 is connected to the head 73. A piston 74 is slideable in the cylinder 73 and a piston rod 75 is connected with the piston 74 and is extended outwardly through a gland 76, which is carried by the head 72. A toothed elongated gear rack 77 is fixed by a fastening member 78 to the piston rod 75 and is disposed in axial alignment with the rod 75.

The shaft 80 has secured thereto a bell crank 82 which is connected by means of a link 83 to a balanced gate valve structure 84. The gate valve structure 84 is conventional and is here

shown as one example of a gate valve structure which may be operated by the suction means hereinbefore described.

In the use and operation of this device with the water wheel 16 in normal operation, the valve plug 35 will be disposed in substantially the position shown in Figure 3. In this position the valve closing members 33 and 37 are in port closing position to close the ports 65 and 66, respectively. At this time, the suction from the pipe 61 caused by the water passing the suction nozzle 64 will be prevented from effecting movement of the piston 74 in either direction. Assuming, however, that the flow of water is such as to cause the water wheel or power member 16 to speed up unduly, the excessive rotation of the shaft 17 will cause the governor 19 to lower the valve plug 35 and establish communication from the suction chamber 39 to the port 66. This suction will be communicated through the pipe 68 to the left end of the cylinder 71 through the head 73. This will pull the piston 74 to the left and rock the gear 79 in a counter-clockwise direction. Rotation of the gear 79 in a counter-clockwise direction will effect counter-clockwise rotation of the shaft 80 so as to close the gate structure 84 and cut off the flow of water to the power member 16. When the power member 16 reduces in speed, the reduction of speed of the governor 19 will permit the spring 55 to raise the valve plug 35 to an intermediate suction port closing position and if the speed of the governor 19 is relatively slow, the spring 55 will raise the valve plug 35 so as to communicate the port 65 with the suction chamber 39 and establish communication between the suction port 29 and the port 65. This will place the suction pipe 65 in communication with the suction pipe 61 and effect movement of the piston 74 to the right. Movement of the piston 74 to the right will cause the gear 79 to rotate in a clockwise direction which will rotate the shaft 80 in the same direction and open the gate structure 84.

A regulating means constructed according to this invention will maintain an even speed of the water wheel or power member which is connected with the water flue 10 so that irrespective of the pressure or flow of water through the flue 10, the power member 16 will be maintained at a substantially constant speed.

What I claim is:

1. A speed regulating means for a water actuated power member interposed in a water duct, said means including a gate interposed in said duct on the intake side of said power member, a suction operated gate operating member connected with said power member, and a suction pipe extending from said operating member and extending into said duct on the outlet side of said power member.

2. A speed regulating means for a water actuated power member connected with a water duct, said means including a gate interposed in said duct on the intake side of said member, a suction operated gate operating member, means connecting said operating member with said gate, a centrifugal governor connected with and operated from said power member, a suction valve connected with said governor, said duct and said operating member, the speed of said governor effecting movement of said suction valve to thereby control the operation of said gate operating member, and a suction pipe connected with said

valve and said duct on the output side of said power member.

3. A speed regulating means for a water actuated power member connected with a water duct, said means including a gate interposed in said duct on the intake side of said member, a suction cylinder, a piston slideable in said cylinder, means connecting said piston with said gate for operation of said valve upon movement of said piston, a centrifugal governor operated from said power member, a suction valve connected to said governor and movable thereby, said suction valve having a pair of spaced apart ports and an intermediate port, a pipe connected with said intermediate port and extending into said 15

duct on the outlet side of said power member, a valve plug connected to said governor and operable in one position thereof to communicate one of said pair of ports with said intermediate port, and in another position thereof to communicate the other of said pair of ports with said intermediate port, said valve plug in a further position thereof cutting off communication between both of said pair of ports and said intermediate port, pipes connecting the opposite ends of said cylinders with said pair of ports, and a suction nozzle carried by said first pipe and disposed within said duct.

NELSON J. PEPIN.
